CLAIM

The ornamental design for a tapered cup, as shown and described.

DESCRIPTION

FIG. 1 is a front perspective view of a first embodiment of a tapered cup, showing our new design;

FIG. 2 is a front elevation view thereof, the right, left and rear elevation views being identical;

FIG. 3 is a top plan view thereof;

FIG. 4 is a bottom plan view thereof;

FIG. 5 is a front perspective view of a second embodiment of a tapered cup showing our new design;

FIG. 6 is a front elevation view thereof, the right, left and rear elevation views being identical;

FIG. 7 is a top plan view thereof;

FIG. 8 is a bottom plan view thereof;

FIG. 9 is a front perspective view of a third embodiment of a tapered cup showing our new design;

FIG. 10 is a front elevation view thereof, the right, left and rear elevation views being identical;

FIG. 11 is a top plan view thereof;

FIG. 12 is a bottom plan view thereof;

FIG. 13 is a front perspective view of a fourth embodiment of a tapered cup showing our new design;

FIG. 14 is a front elevation view thereof, the right, left and rear elevation views being identical;

FIG. 15 is a top plan view thereof; and,

FIG. 16 is a bottom plan view thereof.

The broken lines in the drawings depict portions of the tapered cup that form no part of the claimed design.
